UNITED STATES PATENT OFFICE.

PATRICK M. GREENE, OF HARTFORD, CONNECTICUT, ASSIGNOR TO ROYAL TYPE-WRITER COMPANY, INC., OF NEW YORK, N. Y., A CORPORATION OF NEW YORK.

TYPEWRITING MACHINE.

Application filed July 29, 1924. Serial No. 728,363.

To all whom it may concern:

Be it known that I, PATRICK M. GREENE, a citizen of the United States, and resident of Hartford, in the county of Hartford and 5 State of Connecticut, have invented certain new and useful Improvements in Type-writing Machines, of which the following is a specification.

The usual typewriting key comprises a 10 cup carried by the upturned end of the key lever wherein are retained a washer, a disc or card carrying the character, and a protecting glass. It frequently happens that although this protecting glass is engaged 15 by a ring member which has projections turned under the cup member and consequently is supposed to hold the parts firmly in proper relation, nevertheless the character disc will become displaced.

20 An object of this invention is to provide simple and efficient means for preventing the displacement of the character disc, which means will not add to the cost of manufacture or assembly or increase the 25 number of parts employed in the cap.

Other objects will be apparent from the following detailed description and the appended claims.

In the drawings:

30 Figure 1 is a side elevation of the key lever with the assembled cap in section.

Figure 2 is a top plan view of the key lever, cup and washer.

Figure 3 is a top plan view of the washer.

35 Figure 4 is a side elevation of the same.

Figure 5 is a top plan view and Figure 6 a side elevation of a modified form of washer.

Figure 7 is a top plan view and Figure 40 8 a side elevation of a further modification.

Figure 9 is a top plan view and Figure 10 a side elevation of a still further modification.

Figure 11 is a top plan view of character 45 card shown as embedded in the depressed portions of the washer.

The key lever A of ordinary form has an upturned end provided with a reduced portion B which passes through a similarly 50 shaped opening in a cup member C and also through a similarly shaped opening b in a washer D which fits within the cup. The end of the key lever portion B is riveted so that the lever, cup C and washer D are 55 held rigidly together. Upon the washer D

within the cup C is placed a character disc E, preferably of cardboard and having the desired character printed thereon. Over this is placed a protecting disc F of glass or other transparent material. A ring G 60 fits outside the cup and has an upper inwardly turned edge g which bears on the glass, while the lower edge of the ring G has ears g' that are bent over the bottom of the cup C when the parts are assembled 65 and draw the edge g down on the glass with considerable pressure, the intention being to hold the parts firmly in position.

Notwithstanding this fact it frequently happens that the character disc becomes 70 turned and when this happens it is difficult, if not impossible, to bring it back to proper position without disassembling the cap. In accordance with this invention there is provided a special form of washer which will 75 engage the cardboard character disc and prevent its displacement. Various forms may be devised, and four different modifications are illustrated, in all of which the washer D is so constructed that portions 80 thereof lie in different planes. The pressure of assembly of the parts will therefore cause the raised portions of the washer to be pressed into the cardboard character disc and the disc to be pressed into the lower 85 portions of the washer in such a manner that any relative turning movement is positively prevented when the parts are assembled.

In the form shown in Figures 1 to 4, the 90 washer D has two relieved portions d each of about one quarter of the circumference and separated by equal spaces d'. Between these relieved portions the washer is spaced slightly from the wall of the cup C. The 95 washer is not circular, but would be substantially circular and fit loosely within the cup if these relieved portions d were cut away. It will be seen that if the pasteboard character disc E is pressed down upon the 100 washer D, the raised or relieved portions d will be imbedded in the cardboard, while the cardboard will be pressed down into the spaces d'. Since the washer is held against rotation, it is evident that the character 105 disc will also be positively held against displacement.

It is obvious that washers of the desired form can be produced readily by stamping and that there is no more difficulty in assem- 110

bling the parts than in the old form. Nevertheless the character disc will be held against any displacement without any special attention being given the matter of assembly. No additional parts are necessitated and the pressure of the character disc into the desired relation to the washer does not produce any noticeable distortion. Various forms of washer may be devised which have the same general characteristics.

In the modifications shown in Figures 5 and 6, the washer D' the portions *d* of the edge of the washer are the same as those shown in the first form, but the intervening portions *e* are pressed down instead of being removed as shown in Figure 3. When the parts are assembled the high portions *d* will be embedded in the character disc.

In the modification shown in Figures 7 and 8, the washer D² has three relieved portions *f* which are of less extent than the portions *d* of the preceding forms, but are separated by narrow cut away portions *f'*. The action of the parts when assembled is the same as in the preceding cases.

In the modification shown in Figures 9 and 10, the raised or relieved edge of the washer D³ is divided into a plurality of portions, preferably four, which are angularly arranged. The effect, as clearly shown in the drawings is to give a kind of spiral arrangement or fractions of a multiple screw thread. These portions *H* all have their upper ends lying in a plane and their lower ends lying in a plane parallel thereto, but of course this is not essential and the particular form of these angular portions *H* may be widely varied.

It is obvious that further modifications may be readily devised without departing in any way from the spirit of the invention, and the invention is to be regarded as lim-

ited only by the scope of the appended claims.

I claim as my invention:

1. A key cap comprising a cup, a washer fitting therein, a character disc, and means for pressing the character disc into engagement with the washer, the latter being provided with engaging portions lying in different planes, whereby the disc and washer are positively held in fixed relation when assembled.

2. A key cap comprising a cup, a washer fitting therein, a character disc, and means for pressing the character disc into engagement with the washer, the latter being provided with edge portions lying in different planes, whereby the disc and washer are positively held in fixed relation when assembled.

3. A key cap comprising a cup, a washer fitting therein, a character disc, means for pressing the character disc into engagement with the washer, and means on the washer lying in different planes which positively engage the disc when the parts are assembled and hold it against relative rotation.

4. A key cap comprising a cup, a washer fitting therein, a character disc, and means on the washer lying in different planes which positively engage the disc when the parts are assembled and hold it against relative rotation.

5. A key cap comprising a cup, a washer fitting therein, a character disc, and discontinuous surface portions on the washer into interlocking engagement with which the disc is pressed when the parts are assembled to hold the disc against rotation.

In testimony whereof, I have hereunto subscribed my name.

PATRICK M. GREENE.
